UNITED STATES PATENT OFFICE.

WILLIAM H. MANN, OF BUFFALO, NEW YORK.

DESIGN FOR A BOX.

SPECIFICATION forming part of Design No. 19,697, dated March 11, 1890.

Application filed February 12, 1889. Serial No. 299,637. Term of patent 7 years.

To all whom it may concern:

Be it known that I, WILLIAM H. MANN, a citizen of the United States, residing at Buffalo, in the county of Erie and State of New York, have invented a new and original Design for a Box, of which the following is a specification, reference being had to the accompanying illustration, forming a part thereof, and in which—

10 Figure 1 is a perspective view of the box, and Fig. 2 a plan of the same, the cover and its attached ornaments being removed.

This design consists, essentially, in the peculiar configuration and ornamentation of the box, as hereinafter first fully set forth and described, and then pointed out in the claim.

To carry out my newly-discovered design I provide the body of the box with a bottom having its edges projecting and upwardly and inwardly curled. I also provide the cover with a top, the edges of which are also projecting and upwardly and inwardly curled. The box so far described is very ornamental

in appearance, the curled edges giving a neat and tasty look to the box; but, to further ornament the same, upon the cover the representation of a spotted egg and fowl is placed, the whole being tinted in suitable and harmonizing colors. 25

Having thus fully described my design, I 30 claim—

The design for a box herein shown and described, the same comprising the body portion and rim having the bottom and top portions projecting and the edges or corners upwardly and inwardly curled, the egg, and the figure on the top of the egg, as and in the manner set forth. 35

In testimony whereof I have hereunto set my hand in the presence of two subscribing 40 witnesses.

W. H. MANN.
